UNITED STATES PATENT OFFICE

2,596,205

PARTITIONED TRAY OR HOLDER

Kenneth T. Butterly, Kalamazoo, Mich., assignor
to Sutherland Paper Company, Kalamazoo,
Mich., a corporation of Michigan

Application February 12, 1951, Serial No. 210,606

5 Claims. (Cl. 229—28)

1

This invention relates to improvements in partitioned tray or holder.

The main objects of this invention are:

First, to provide a partitioned tray or holder for use in the packaging and displaying of fragile articles such as bakery products and other products where compartments are desired and particularly where it is desired to use a transparent wrapper facilitating the display of the packaged product.

Second, to provide a partitioned tray or holder which may be formed of an integral blank and one in which the parts effectively coact in supporting each other in erected position.

Third, to provide a structure having these advantages which may be shipped in the knock-down and quickly erected for use.

Objects relating to details and economies of the invention will appear from the description to follow. The invention is pointed out in the claims.

A preferred embodiment of the invention is illustrated in the accompanying drawings, in which:

Fig. 1 is a perspective view of a completed package embodying my invention, articles such as cookies or wafers being conventionally illustrated within the package.

Fig. 2 is a perspective view of the tray or holder fully erected.

Fig. 3 is a perspective view illustrating the parts in partially erected position and steps in erecting.

Fig. 4 is an enlarged transverse section on a line corresponding to line 4—4 of Fig. 1.

Fig. 5 is a plan view of the blank of the tray or holder illustrated.

The embodiment of my invention illustrated is formed of a blank cut and scored to provide bottom members 1 and 2 which are spaced in the blank by the longitudinal partition member 3. The bottom edge of this longitudinal partition member is hingedly connected at 4 to the inner edge of the bottom member 1. The longitudinal partition member has spaced slits 5 extending from its upper edge providing a swingable strap-like hinge member 6 which is hingedly connected at 7 to the longitudinal partition member 3 and at 8 to the inner edge of the bottom member 2. When the partition member 3 is swung to erected position, the hinge member 6 swings downwardly on its hinge connection 7 as is shown in Figs. 2, 3 and 4 and the bottom member 2 is positioned in edge to edge relation with the bottom member 1.

2

Side walls 9 are hingedly connected at 10 to the outer edges of the bottom members 1 and 2. Transverse partition members 11 are hingedly connected to the ends of the side walls at 12 to be swung to a position at right angles relative to the side walls and to the longitudinal partition member. The longitudinal partition member is provided with vertical slits 13 spaced from the slits 5 and aligned with the hinging scores 12 connecting the transverse partition members to the side members. The transverse partition members 11 have tongues 14 on their swinging edges engageable in these slits, the tongues having depending portions 15 extending below the bottoms of the slits 13 when the parts are in fully erected position. When fully erected, the end edges 16 of the transverse partition members 11 are in supporting engagement with opposite sides of the longitudinal partition member while the depending portions 10 of the tongues 14 are in opposed retaining engagement with the longitudinal partition member.

To facilitate engagement of the tongues 14, the longitudinal partition member has diagonal slits 17 opening to the slits 13. The resulting tongues 18 on the inner edge of the bottom member 2 are desirably turned upright and positioned against the longitudinal partition member as indicated in Figs. 2 and 3 and coact with the hinge member 6 in supporting the inner edge of the bottom member 2 in erected position.

When erected, the tray provides a plurality of compartments in which baked goods or other articles such as indicated at 19 may be arranged and the loaded tray provided with a wrapper 20 which is desirably of transparent heat sealable material. The side walls in the embodiment illustrated are recessed at 21 to facilitate the displaying of the articles arranged in the two intermediate compartments. While my tray or holder in the embodiment illustrated is especially designed for use in the packaging of baked goods or other fragile articles, it is desirable for use in packaging other articles. The structure may be shipped in the flat as is shown in Fig. 5 and readily erected, certain of the steps being illustrated in Fig. 3 and when erected, the parts coact with each other to support the tray in erected position.

I have illustrated and described my invention in a highly practical embodiment thereof. I have not attempted to illustrate or describe other embodiments or adaptations as it is believed that this disclosure will enable those skilled in the

art to embody or adapt my invention as may be desired.

Having thus described my invention, what I claim as new and desire to secure by Letters Patent is:

1. A partitioned holder or tray comprising bottom members, a longitudinal partition member hingedly connected at its bottom edge to the inner edge of one bottom member and having spaced cut edges extending downwardly from its upper edge providing a central swingable strap-like hinge member hingedly connected to the longitudinal partition member and to the inner edge of the other bottom member, said longitudinal partition member having vertical slits in its upper edge spaced longitudinally from said strap hinge member, side wall members hingedly connected to the outer edges of said bottom members, and transverse partition members hingedly connected to the ends of said side wall members and having tongues on their swinging edges disposed in the said slits in said longitudinal partition member when the tray or holder is erected with the outer edges of the transverse partition members in opposed abutting supporting relation to the longitudinal partition member, the said tongues having depending portions oppositely engaging the longitudinal partition member whereby the side walls and partition members are held in erected position providing a plurality of compartments.

2. A partitioned holder or tray comprising bottom members, a longitudinal partition member intermediate said bottom members and hingedly connected at its bottom edge to the inner edge of one bottom member and having spaced cut edges extending downwardly from its upper edge providing a central swingable strap-like hinge member hingedly connected to the longitudinal partition member and to the inner edge of the other bottom member, said longitudinal partition member having vertical slits in its upper edge spaced longitudinally from said strap hinge member, side wall members hingedly connected to the outer edges of said bottom members, and transverse partition members hingedly connected to the ends of said side wall members and having tongues on their swinging edges disposed in the said slits in said longitudinal partition member whereby the side walls and partition members are held in erected position providing a plurality of compartments.

3. A partitioned holder or tray comprising bottom members, a longitudinal partition member hingedly connected at its bottom edge to the inner edge of one bottom member and having a swingable hinge member hingedly connected thereto

and to the inner edge of the other bottom member whereby said bottom members may be disposed edge to edge with the longitudinal partition member in erected position common to both bottom members, side wall members hingedly connected to the outer edges of said bottom members, and transverse partition members hingedly connected to the ends of said side wall members and having tongues on their swinging edges, and said longitudinal partition member having slits therein adapted to receive said tongues with the end edges of the transverse partition members in opposed abutting supporting relation to the longitudinal partition member, said tongues having interlocking engagement with said longitudinal partition member when the tray holder is erected.

4. A partitioned holder or tray comprising bottom members, a longitudinal partition member hingedly connected at its bottom edge to the inner edge of one bottom member and having a swingable hinge member hingedly connected thereto and to the inner edge of the other bottom member whereby said bottom members may be disposed edge to edge with the longitudinal partition member in erected position common to both bottom members, side wall members hingedly connected to the outer edges of said bottom members, and transverse partition members hingedly connected to the ends of said side wall members and having tongues on their swinging edges engageable with said longitudinal partition member with the transverse partition members in supporting and supported relation to the longitudinal partition member.

5. A partitioned holder or tray comprising bottom members, a longitudinal partition member hingedly connected at its bottom edge to the inner edge of one bottom member, said longitudinal partition member having a swingable strap-like hinge member swingably connected to the longitudinal partition member and to the inner edge of the other bottom member, side wall members hingedly connected to the outer edges of said bottom members, and transverse partition members hingedly connected to the ends of said side wall members and interlockingly and supportedly engageable with said longitudinal partition member.
